CUSPIDOR CARRIER AND HANDLER

Charlie T. Balochi, Roanoke, Va.

Application March 20, 1937, Serial No. 132,141

2 Claims. (Cl. 294—32)

My invention relates to improvements in cuspidor carriers and handlers and the primary object thereof is to provide a simply constructed inexpensive and efficient device of this character 5 adapted for use in stacking cuspidors, carrying a stack thereof, and depositing the cuspidors successively from the bottom of the stack.

To the accomplishment of the above, and subordinate objects presently appearing, a preferred 10 embodiment of my invention has been illustrated in the accompanying drawing, set forth in detail in the following description, and defined in the claims appended hereto.

In said drawing:—

15 Figure 1 is a view in side elevation of a carrier and handler constructed in accordance with my invention, and

Figure 2 is a view in vertical longitudinal section taken on the line 2—2 of Figure 1.

20 Describing my invention in detail, with reference to the drawing by numerals, the improved carrier and handler comprises a cylinder 1 closed at its top as at 2 and outwardly flared at its bottom as at 3. The cylinder 1 may be made of any 25 suitable light metal and of a diameter slightly larger than that of the average cuspidor to loosely fit over the latter. A U-shaped handle 4 is secured to the cylinder 1, at diametrically opposite points at the top thereof as by rivets 5. A pair of 30 leaf springs 6 are riveted, or otherwise secured, as at 7, to the cylinder 1 to depend therefrom upon opposite sides thereof in vertical alignment with the ends of the handle bar 4, respectively. A pair of 35 triangular block-like grips 8 are secured to the lower ends of the springs 6, respectively, as by screws 9 to extend through a pair of elongated slots 10 provided in the casing 1, said grips extending into the interior of said casing as shown in Figure 2. The grips 8 are each formed with 40 substantially right angular upper and lower lifting and camming faces 11 and 12, respectively, on their inner edges. The upper faces 11 are designed to fit under the outwardly flaring top flange 13 of the usual type of cuspidor 14 to lift 45 the latter as will be clear. The springs 6 tension the grips 8 against separated movement so that said faces 11 are normally located for engagement with said flange 13 as shown in Figure 2. The camming faces 12 of the grips 8 are so designed 50 that if the cylinder 1 is placed over a cuspidor 14 said faces and grips 8 will be cammed outwardly of the cylinder 1 by engagement with the upper edge of said flange 13 whereby if the cylinder 1 is moved downwardly over a cuspidor 14 said 55 grips 8 will take under the flange 13 with a snap

action. The grips 8 are so located on the cylinder 1 that when the latter is placed over a cuspidor and upon the floor or ground said grips will engage the sides of the flange 13 well under the top edge of the same. As will be clear if the cylinder 1 is manipulated to stack a cuspidor held between said grips 8 on top of another and the cylinder 1 then lowered the grips 8 will be cammed outwardly in the manner previously explained to take under the flange 13 of the lower cuspidor 14. In this 10 manner a stack of cuspidors may be quickly formed in the cylinder and carried away the lowermost one being supported by the grips 8 and the remaining ones by said lower one.

5 Manipulative means are provided for separating the grip 8 at will to release a cuspidor 14 as follows. A pair of grips releasing bars 15 are suitably secured at their lower ends to the grips 8, respectively, to extend upwardly therefrom above the top of the cylinder 1. Above the cylinder 1 the releasing bars 15 are each provided with an inwardly extending end 16. The inwardly extending ends 16 project through suitable slots 17 in the sides of the handle bar 4 into the space between said bar 4 and the top 2 of the cylinder. 20 The extremities of the ends 16 extend into opposite ends of a tube-like hand grip 18 whereby the latter is suspended between the handle bar 4 and the top 2 of the casing 1. The described connection between the ends 16 of the releasing bars 15 25 and the hand grips 18 is such that said ends 16 are pivotally and slidably mounted in said hand grip as will be clear. The releasing bars 15 are pivotally mounted, as by studs 19 extending through the ends of the handle bar 4 and the 30 cylinder 1 and having sufficient play in said handle bar and cylinder to permit the releasing bars to be swung outwardly of the cylinder 1. As will be manifest if the hand grip 18 is depressed the 35 releasing bars will be swung in the manner described against the tension of the springs 6 to move the grips 8 outwardly and thereby release a cuspidor held therebetween.

The construction, operation and advantages of my invention will, it is believed, be clear from the 45 foregoing description thereof.

Manifestly modifications in details described may be resorted to without departing from the inventive concept and right is herein reserved to all such modifications falling within the scope 50 of the claims appended hereto.

What is claimed is:—

1. A device of the class described comprising a cylinder provided with a pair of diametrically opposed slots adjacent its lower end, a handle bar 55

secured to its upper end and spanning the same, a pair of leaf springs secured to the cylinder to depend therefrom in vertical alignment with said slots, respectively, a pair of block-like grips secured to the lower ends of said springs, respectively, to project through said slots into said cylinder and tensioned against separative movement by said springs, and manipulative means for separating said grips comprising a pair of bars depending from the top of said cylinder and secured at their lower ends to said grips, respectively, said bars being swingably mounted on said cylinder for separative movement of their lower ends, means for swinging said bars comprising an extension on the upper end of each bar overlying the top of said cylinder below said handle bar, and a sleeve-like hand grip telescoping over the extensions of said bars.

2. A device of the class described comprising a

container provided with a pair of opposed slots adjacent its lower end, a pair of leaf springs secured to the container to depend therefrom in alignment with said slots, a pair of block-like grips secured to the lower ends of said springs to project through said slots into said container and tensioned against separative movement by said springs, and manipulative means for separating said grips comprising a pair of bars depending from the top of said container and secured at their lower ends to said grips, said bars being swingably mounted on said container for separative movement of their lower ends, means for swinging said bars comprising an extension on the upper end of each bar overlying the top of said container, and a sleeve like hand grip telescoping over the extensions of said bars.

CHARLIE T. BALOCHI.
